(57) **CLAIM**

The ornamental design for a pet bed frame, as shown and described.

DESCRIPTION

FIG. 1 is a perspective view of a pet bed frame showing my new design;

FIG. 2 is a right side view thereof;

FIG. 3 is a left side view thereof;

FIG. 4 is a top side view thereof;

FIG. 5 is a bottom view thereof;

FIG. 6 is a front view thereof;

FIG. 7 is a back view thereof; and,

FIG. 8 is another perspective view thereof.

The broken lines illustrate portions of the pet bed frame that do not form a part of the claimed design.

1 Claim, 8 Drawing Sheets
